UNITED STATES PATENT OFFICE.

GEORGE A. WOOD, OF SOUTHBURG, CONNECTICUT.

PROCESS FOR MAKING HAND-TOOLS.

1,139,392.

Specification of Letters Patent. Patented May 11, 1915.

Application filed February 25, 1914. Serial No. 820,969.

To all whom it may concern:

Be it known that I, GEORGE A. Wood, a citizen of the United States, residing at Southington, in the county of Hartford, 5 and State of Connecticut, have invented a new and Improved Process for Making Hand-Tools, of which the following is a specification.

My invention relates more especially to 10 that class of hand tools in which a handle is rigidly secured at one end of the tool, the opposite end of which constitutes the operative part, such as a screw driver, chisel, or the like, and an object of my invention, 15 among others, is to provide a tool of this class in which the handle shall be firmly secured in place and in which there shall be no perceptible line of division between the tool bolster and ferrule.

20 One form of tool embodying my invention and in the construction and use of which the objects herein set out, as well as others, may be attained, is illustrated in the accompanying drawings, in which—

25 Figure 1 is a side view of a portion of a tool and handle secured thereto in accordance with my invention, and with parts broken away to show construction. Fig. 2 is an end view of the same. Fig. 3 is a 30 detail view showing the form of the metal piece in a preliminary step in the operation. Fig. 4 is an end view of the same.

In the accompanying drawings the numeral 6 indicates the blade of a tool, as of 35 a screw driver, 7 the bolster, and 8 the stem or shank extending through the handle. A head 9 at the end of the shank may be employed to secure the handle 10 in place.

40 In constructing a tool according to my invention the ferrule 11 is formed integral with the bolster 7 so that there is no joint between the ferrule and bolster, and the exposed metallic part of the tool will always 45 present a smooth continuous surface. The end 12 of the tool handle will be inserted into the socket formed by the ferrule, and the handle may be secured in any desired manner, it not being absolutely essential 50 that the head 9 shall be employed for this purpose.

In constructing my improved tool I em-

ploy a piece of stock, one part 13 of which will constitute the blade and upon which a flange 14 is made in any desired manner, 55 the part 15 extending on the opposite side of the flange from the blade being intended for the shank. The flange 14 is then turned up into a cup shape, as shown in Fig. 1, and the parts are then finished, the blade 60 being formed into such tool as may be desired and the bolster and ferrule being finished to proper shape.

I contemplate, in one form of tool, that 65 that part of the stock intended for the bolster shall be swelled as denoted by the numeral 16 in Fig. 3 of the drawing, and this will enable, in some instances, an increase in the depth of the socket into which 70 the end 12 of the handle is inserted, by producing, as with a cutting tool, a groove in the bottom of the socket about the base of the shank 15, and as shown in dotted lines in Fig. 3 of the drawing. This is not material to my invention, but it may be made 75 use of in some instances where a hollow milling tool may be employed to finish the inside of the ferrule, the milling tool being inserted down into this swelled part of the bolster to produce the groove. In most 80 instances I contemplate that the entire tool, including the ferrule, shall be formed by forging, or like process.

While I have shown and described herein 85 the preferred steps for making my improved tool, and have also shown the latter in its preferred form, these steps and the construction of the tool may be changed to a greater or lesser degree and yet be within the spirit and intent of the invention. 90

I claim—

1. The process of making a tool that consists in forming a lateral flange upon a rod of stock at a distance from each end thereof with a shank upon one side of said 95 flange, and then turning said flange to form a socket with its axis coincident with that of the tool shank.

2. The process of making a tool that consists in forming a lateral flange on a rod 100 of stock at a distance from each end thereof, forming an enlargement on said stock at one side of and next to said flange, bending said flange to form a socket with its

axis coincident with that of said stock, and forming a cut in the enlarged part and below said flange, said cut constituting a continuation of the socket formed by the flange.

3. The process of making a tool that consists in forming an enlargement upon a rod of stock at a distance from each end there-

of, forming the rod into a tool shank upon one side of the enlargement, and then forming said enlargement into a socket with its axis coincident with that of the tool shank.

GEORGE A. WOOD.
